US00D772559S

(12) **United States Design Patent** (10) **Patent No.:** **US D772,559 S**
Binder et al. (45) **Date of Patent:** **** Nov. 29, 2016**

(54) **PACKAGING FOR A WOUND THERAPY SYSTEM**

(71) Applicant: **Smith & Nephew PLC**, London (GB)

(72) Inventors: **Ian Binder**, Chippenham (GB); **John Cowan-Hughes**, Bristol (GB); **Beverley Love**, Hessle (GB); **Mark Russell**, Hull (GB); **Peter Sleight**, Cottingham (GB); **Philip Walsh**, Bristol (GB)

(73) Assignee: **Smith & Nephew PLC**, London (GB)

(**) Term: **15 Years**

(21) Appl. No.: **29/563,987**

(22) Filed: **May 10, 2016**

Related U.S. Application Data

(63) Continuation of application No. 29/492,878, filed on Jun. 3, 2014, now Pat. No. Des. 758,851.

(57) **CLAIM**

The ornamental design for packaging for a wound therapy system, as shown and described.

DESCRIPTION

FIG. 1 is a top, front and left side perspective view of the packaging for a wound therapy system showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top, front and left side perspective view of the packaging for a wound therapy system in a partially open configuration;

FIG. 9 is a front elevation view of a packaging for a wound therapy system in a fully open configuration;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines in the drawings depict unclaimed subject matter and form no part of the claimed design.

1 Claim, 13 Drawing Sheets
